UNITED STATES PATENT OFFICE.

EMMA L. TRIGG, OF NASHVILLE, TENNESSEE.

SHOULDER-BRACE.

1,050,257.

Specification of Letters Patent. Patented Jan. 14, 1913.

Application filed August 17, 1911. Serial No. 644,574.

To all whom it may concern:

Be it known that I, EMMA L. TRIGG, a citizen of the United States, residing at Nashville, in the county of Davidson and State 5 of Tennessee, have invented certain new and useful Improvements in Shoulder-Braces, of which the following is a specification, reference being had to the accompanying drawings.

10 This invention relates to new and useful improvements in shoulder braces and more particularly to that class which can be adjusted to suit any size person and has for its object to provide a device of this character 15 which will possess advantages in points of efficiency, durability, is inexpensive of manufacture and at the same time is simple in construction and operation.

With the above and other objects in view, 20 the invention consists in the novel features of construction and the combination and arrangement of parts hereinafter described, pointed out in the claims and shown in the accompanying drawings, in which—

25 Figure 1 is a perspective view of my improved brace; and Fig. 2 is a detail sectional view taken through one of the buckles to illustrate the connection between the shoulder straps and the shoulder.

30 Referring more particularly to the drawings 1 indicates the shoulder loops, which are adapted to pass around the shoulders of the wearer, and across the back a short distance and have their free ends secured to the 35 pentagon-shaped holder 2. These loops are to be made of elastic webbing or any other pliable material desired and can be adjusted to various sizes by means of the buckles 3 of the ordinary construction.

40 Secured to the lower side of the holder 2 is a vertically depending elastic back-strap 4, which latter has a belt 5 secured to its lower end adapted to pass around the waist of the

wearer and its ends secured together by means of the buckle 6 secured to one of the 45 free ends of the belt, said back strap being provided with an adjusting buckle 3'.

From the foregoing it will be seen that a shoulder brace constructed in accordance with my invention provides great freedom 50 of movement for the wearer and is simple in construction and inexpensive of manufacture.

While I have shown and described the preferred form of my invention, it will be 55 obvious that various changes in the details of construction and in the proportions may be resorted to for successfully carrying my invention into practice without sacrificing any of the novel features or departing from 60 the scope thereof.

Having thus described the invention what is claimed is:

As a new article of manufacture, a shoulder brace comprising a pentagonal frame 65 consisting of a continuous piece of wire adapted to rest below the shoulder blades of the wearer, shoulder straps permanently secured at one end to the upper adjacent sides of the frame, the said shoulder straps forming loops and their opposite ends being adjustably connected with the next adjacent sides of the frame below the upper sides thereof to which the opposite ends are connected, a waist belt, a vertically extending 75 back strap permanently secured at one end to the said belt and the upper end of said back strap being adjustably connected to the lower side of the frame substantially as and for the purpose described. 80

In testimony whereof I hereunto affix my signature in the presence of two witnesses.

EMMA L. TRIGG.
